DESIGN FOR A TRAVELING BAG

Elizabeth Nightingale Graham, New York, N. Y.

Application March 6, 1944, Serial No. 112,793

Term of patent 14 years

(Cl. D87—5)

To all whom it may concern:

Be it known that I, Elizabeth Nightingale Graham, a citizen of the United States of America, residing in New York city, county of New York, and State of New York, have invented a new, original, and ornamental Design for a Traveling Bag, of which the following is a specification, reference being had to the accompanying drawing, forming part thereof, wherein,

The rear of the traveling bag is substantially the same in appearance as the front shown.

The characteristic features of my design reside in the traveling bag disclosed, and having the specific locking member positioned on the lower end of the bag, all as shown.

I claim:

The ornamental design for a traveling bag, substantially, as shown and described.

ELIZABETH NIGHTINGALE GRAHAM.
